ELECTROMAGNETIC TRIP CIRCUIT INTERRUPTERS

George G. Grissinger, Wilkinsburg, and Jerome Sandin and Ture Lindstrom, Pittsburgh, Pa., assignors to Westinghouse Electric Corporation, East Pittsburgh, Pa., a corporation of Pennsylvania

Application June 23, 1951, Serial No. 233,212

18 Claims. (Cl. 200—109)

This invention relates to circuit interrupters and more particularly to trip devices for circuit interrupters which are operable to instantaneously trip the breaker on overload currents above a predetermined value and after a time delay on lesser overload currents.

An object of the invention is to provide a circuit interrupter having a current responsive trip device embodying adjusting means for selectively determining the minimum overload current at which the trip device will instantaneously trip the breaker.

Another object of the invention is to provide a circuit interrupter having an electromagnetic trip device comprising an armature operable to trip the interrupter and a fixed core member for producing a differential pull on the armature and manual means for adjusting the armature to vary the differential pull on the armature.

Another object of the invention is to provide a circuit interrupter having an electromagnetic trip means including an armature and embodying means for maintaining a substantially constant bias on the armature during its entire travel.

Another object of the invention is to provide a circuit interrupter having an electromagnetic trip device including an adjustable armature embodying means providing substantially the same spring bias on the armature in each of the adjusted positions.

Another object of the invention is to provide a circuit interrupter having an electromagnetic trip device including a movable armature embodying a movable pivot and biasing means adjacent the pivot whereby, upon deenergization of the magnet, an air gap is established at the pivot end of the armature to effect quick retraction of the armature at the other end.

The novel features that are considered characteristic of the invention are set forth in particular in the appended claims. The invention itself, however, both as to structure and operation, together with additional objects and advantages thereof, will be best understood from the following detailed description thereof when read in conjunction with the accompanying drawings:

In said drawings:

Fig. 1 is a vertical sectional view of a circuit interrupter embodying the invention.

Fig. 2 is an enlarged sectional view of the trip device.

Fig. 3 is a sectional view taken on line III—III of Fig. 2 showing the tripping electromagnet.

Fig. 4 is a sectional view taken on line IV—IV of Fig. 3 showing the adjusting means for the armature.

Fig. 5 is a fragmentary view of a portion of the enclosing casing for the trip device showing the graduations for setting the adjustable armature.

Fig. 6 is a view similar to Fig. 3 but showing a modification of the electromagnetic trip device;

Fig. 7 is a top view of Fig. 6; and

Fig. 8 is a detail view of a portion of Fig. 3 showing the means for adjusting the magnet core.

Referring to Fig. 1 of the drawings, the circuit interrupter operating mechanism illustrated is of the three-pole

2

type and is of the same general construction as fully described in Patent No. 2,083,304, issued June 8, 1937, to Ture Lindstrom and assigned to the assignee of the present invention. For a more detailed description of the construction and operation of the circuit interrupter mechanism, reference may be had to the above-mentioned patent.

The circuit breaker comprises, in general, a casing 11 and a removable cover 13 both of molded insulating material, stationary contact means 15, cooperating movable contact means 17, an operating mechanism 19 and a trip device 21.

Three sets of stationary and movable contact means 15 and 17 are provided forming the three poles of the breaker. The movable contact means 17 for the several poles are mounted on contact members 23 and the movable contact members 23 for the center pole are pivotally mounted on a movable switch member 25, and are biased toward the stationary contact means 15 relative to the switch member 25 by springs 22.

The switch member 25 is pivotally mounted by means of a pivot pin 29 in a U-shaped main frame 31 which also supports the circuit interrupter operating mechanism 19. The switch members for the outer poles are connected to the center pole switch member 25 for simultaneous movement therewith by means of a rigid tie bar 33 which extends transversely across the three poles of the breaker, each of the switch members being securely clamped to the tie bar and insulated therefrom.

The electrical circuits for the several poles of the circuit interrupter are the same, for which reason only the circuit for the center pole will be described. This circuit extends from an upper terminal 45 through a conductor 47, the stationary and movable contact means 15—17, a flexible conductor 49, a conductor 51 and an energizing conductor 53 for the trip device 21 to a lower terminal 55.

The operating mechanism 19 (Fig. 1) is mounted in the main frame 31 and includes a toggle comprising a pair of toggle links 57 and 59 having one end pivotally connected to the center-pole switch member 25, a carrier lever 61 for releasably restraining the other end of the toggle 57—59 in operative position, a channel-shaped operating member 63, an overcenter spring 65 for connecting the adjusting member 63 to the knee 67 of the toggle, and an operating handle 69.

The main frame 31 is disposed below the contact means and is rigidly secured to the base of the casing 11 by means of screws 71 and 73. The screw 73 extends through the conductor 51 and serves to secure the conductor as well as the frame 31 to the casing. One end of the toggle link 57 is pivotally connected to the center-pole switch member 25 by a pivot pin 77 and the other end of the toggle link 57 is pivotally connected by means of the knee pivot pin 67 to the toggle link 59.

The lower end of the overcenter spring unit is pivotally connected to the lower end of the operating member 63 by means of a pivot pin 81 and a pair of supporting ears 83 projecting from the operating member 63. The operating member 63 is pivotally supported on the main frame 31 by means of a pivot pin 85. The lower end of toggle link 59 is pivotally connected to the carrier lever 61 by means of pivots 87, only one of which is shown.

The carrier lever 61 is pivotally mounted in the main frame 31 by means of a pivot pin 89 at the apex of the bell crank levers. Clockwise movement of the carrier lever 61 is normally prevented by a latching lever 91 comprising a pair of spaced parallel levers which are joined by integral yokes 93 and 95 and pivotally mounted on a pivot pin 97 supported in the main frame 31. The yoke 93 of the latching member 91 normally engages the upper end of the carrier lever 61 and restrains the car-

rier lever in operative position. The free lower end of the latching lever 91 carries a pivoted latch engaging pawl 99 supported on the yoke 95 of the latching lever, the pawl 99 and the latching lever 91 being manually restrained by the trip device 21.

When the trip device functions, the pawl 99 and the latching lever 91 are released thereby permitting counterclockwise movement of the latching lever under the biasing influence of the overcenter spring 65. This movement of the latching lever causes the yoke 93 to release the carrier lever 61 which is then moved clockwise about its pivot 89 by the overcenter spring 65 and the force exerted by the contact springs 27. This causes movement and collapse of the toggle 57-59 toward the base of the casing 11 and simultaneous opening of the contact for all of the poles of the breaker.

In order to reset the mechanism following an automatic opening operation, the operating handle 69 is moved in a clockwise direction to the "off" position causing the operating member 63 to engage and reset the carrier lever 61 and the latching lever 91 to their latched positions. The contacts are then closed by moving the handle 69 in a counterclockwise direction to the "on" position.

The circuit interrupter is opened manually by movement of the operating handle 69 in a clockwise direction from its Fig. 1 position to the "off" position. When the handle has been moved a short distance, a projection (not shown) on the operating member 63 engages the yoke 75 of the toggle link 57 and starts the knee 67 of the toggle 57-59 toward the base of the breaker. At the same time, the spring 65 moves across the center line of the toggle link 59 and now exerts a force in a direction to move the knee of the toggle toward the base. The movement of the several parts of the operating mechanism is now automatic and the contacts for all of the poles of the breaker are opened simultaneously with a snap action.

The contacts are closed following a manual opening operation by moving the operating handle counterclockwise back to the "on" position. This movement carries the line of action of the spring 65 over the center line of the toggle link 59 whereupon the springs 65 exert a force biasing the knee of the toggle 57-59 outwardly away from the base, causing straightening of the toggle and closing of the contacts with a snap action.

The trip device 21 comprises a unitary structure, the several elements of which are mounted on a panel or base 101 (Figs. 1 and 2) of insulating material removably mounted on the base of the casing 11. The trip device is enclosed in a casing 102 and comprises generally a bimetal element 103 and an electromagnet 105 for each pole of the breaker. The conductor 53 forms a loop 107 and is secured by means of rivets 111 to a bracket 109. The rivets 111 also serve to rigidly secure one end of the bimetal element 103 to the conductor 53. The bimetal element 103 extends substantially parallel to the upper leg of the loop 107 of the conductor 53 which serves as a heater element for the bimetal element. The bracket 109 is firmly secured to the panel 101 by means of rivets 113 thereby rigidly securing the conductor 53 and the bimetal element to the panel.

A trip bar 115 of insulating material is pivotally supported by means of brackets 117 (only one being shown) which are suitably secured to the panel 101. The trip bar extends across all of the poles of the breaker and is adapted to be operated by the thermal trip device on the electromagnetic trip device of any pole to effect release of the operating mechanism and opening of the contacts. Secured to the trip bar 115 is a latch member 119 which engages and restrains an intermediate latch 121. The latch 121 is pivotally mounted on a pin 123 in the bracket 117 and is provided with a latching portion which engages the pawl 99 and restrains the latching lever 91 and the operating mechanism in closed position. Also secured to the trip bar 115 is an extension 125 with which an adjusting screw 127 on the free outer end of the bimetal

element 103 is adapted to cooperate to operate the trip bar.

Upon the occurrence of an overload current below a predetermined value of, for instance, from 300% to 1100% of normal rated current in the circuit of any pole of the breaker, the bimetal element 103 associated with the affected pole is heated by the flow of excessive current through the loop 107 of the conductor 53 and when heated a predetermined amount deflects toward the trip bar 115 and rotates the trip bar counterclockwise about its pivot. This movement of the trip bar releases the latch 121 whereupon the force of the operating springs 65 (Fig. 1) causes opening of the breaker contacts in the previously described manner.

The circuit breaker is tripped open instantaneously upon the occurrence of overload currents of from 300% to 1100% or more of normal rated current, or on short-circuit currents by means of the electromagnetic trip means 105. The electromagnet 105 comprises a fixed U-shaped core member 129 (Figs. 1 and 2) secured to the bracket 109 by means of screws 130 and 132, and a pivoted armature 131. The armature 131 is pivotally supported by means of a pin 133 in the armature having its ends engaging in slightly elongated slots 135 in brackets 137 secured one on each side of one leg 136 of the core member 129. The armature 131 is biased to an unattracted position by means of a compression spring 139 having one end seated in a spring seat 141 in the fixed core member 129 and the other end seated in a spring seat 143 in the armature 131 adjacent the pivoted end thereof. By placing the spring 139 close to the pivot 133, the biasing force of the spring is kept substantially constant throughout the travel of the armature and in each of the adjusted positions thereof. The other leg 145 of the U-shaped core member opposite the pivot for the armature forms an angular pole face 147 for cooperating with the angular free end of the armature to form a main magnetic air gap.

A differential pull is provided on the armature 131 by means of a magnetic member 149 secured to the end of the leg 145 of the core member 129 and having a formed-over portion 151 cooperating with the back of the free end of the armature 131 to provide a limited path for at least a portion of the magnetic flux to thereby provide a back pull on the armature 131. The core member 129 adjacent the leg 145 is provided with a slot 153 (Figs. 3 and 8) through which extends the screw 132 which secures the core member to the bracket 109. This permits adjustment of the entire electromagnet 105 relative to projection 155 of the trip bar 115 to effect calibration of the magnetic trip device. By loosening the screws 132 and 130, the magnet assembly 105 can be moved to a position relative to the projecting member 155 on the trip bar where actuation of the trip bar 115 by the armature 131 will just release the latch 121. The screws 130-132 are then tightened to hold the magnet in place.

The upper leg of the conductor loop 107 passes through the U of the core member 129 and serves as an energizing means for the electromagnet. Normal current flowing in the circuit of the breaker including the conductor 53 energizes the electromagnet 105 but not sufficiently to attract and operate the armature 131 against the force of the spring 139 and the back pull of the portion 151 of member 149. Upon the occurrence of an overload current of 1000% or more of normal rated current, or a short-circuit current, the electromagnet is energized sufficiently to instantaneously attract and move the armature to the pole face 147 of the fixed core member 129. During this movement the armature 131 engages a projecting member 155 on the trip bar 115 and thereby actuates the trip bar to release the intermediate latch 121, causing an automatic opening operation of the breaker mechanism in the manner previously described.

By making the pivot 133 for the armature 131 (Fig. 3) movable relative to the leg 138 of the U-shaped core member, a slight air gap is provided at this point in the unattracted position of the armature. Upon energization of the electromagnet, the pivoted end of the armature 131 is moved against the pole face of the leg 138 and the opposite or free end of the armature is attracted against the pole face 147 to actuate the trip bar. The spring 139 is located close to the pivot pin 133 of the armature 131 and is relatively strong so that it will always overcome the residual flux at the pivoted end of the armature and the armature will be moved away from the pole face 138, the pin 133 moving to the outer end of the slot 135 as soon as the current is interrupted by the opening operation of the circuit breaker. This slight motion of the pivoted end of the armature away from the pole face 138 increases the reluctance of the remanent magnetic circuit, and the pull at the other end of the magnet will be decreased sufficiently to allow the spring 139 to quickly move the armature to its fully unattracted position.

Means are provided to selectively determine the minimum overload current required to instantaneously trip the breaker. This is accomplished by adjusting the position of the armature 131 relative to the pole face 147 of the fixed core member and the portion 151 of the magnetic member 149 to thereby vary the initial main and secondary air gaps. The means for adjusting the position of the armature 131 includes a member 157 of non-magnetic material suitably secured to the armature 131. The member 157 is angular in shape as shown in Fig. 3 and has an ear 159 formed on the end thereof. An adjusting screw 161 is mounted in the ear 159 and is locked in position by a lock nut 163. The inner end of the screw 161 is rounded and cooperates with a stepped cam 165 secured to a shaft 167 for rotation therewith. The inner end of the shaft 167 passes through a clearance slot 169 in the member 157 and is rotatably seated in a cup-shaped bearing surface 171 (Fig. 4) in the leg 145 of the core member 129. The shaft 167 extends outwardly substantially perpendicular to the plane of the core member 129 and at its outer end has secured thereto a member 175 of insulating material. The member 175 is provided with serrations 177 cooperating with formed-out portions of a leaf spring 179 secured by means of a screw 181 to the panel or base 101 of the trip device. The leaf spring 179 serves the dual purpose of retaining the shaft 167 and cam 165 in the adjusted position and biasing the inner end of the shaft 167 into the cup-shaped bearing surface 171. The member 175 is provided with a reduced portion 183 extending through an opening in the leaf spring 179 to serve as a bearing for the outer end of the shaft 167. The outer end of the portion 183 is accessible from outside the casing 102 through an opening therein and is provided with a slot for receiving a tool whereby the shaft 167 and cam 165 can be rotated.

When the electromagnet 105 is deenergized and the relatively strong spring 139 moves the armature 131 to its unattracted position, the adjusting screw 161 strikes the cam 165. This blow, if struck against a solid stop, may be of sufficient force to bend or deform the ear 159 in which the screw is mounted and thus destroy the calibration of the device. To avoid this, the side wall of the cup-shaped bearing 171 is slanted so that when the screw 161 strikes the cam 165, the inner end of the shaft 167 slides up the side of the bearing surface 171 camming the shaft axially outwardly against the bias of the leaf spring 179 thus resiliently absorbing the blow. The leaf spring 179 then forces the shaft 167 back to its normal position in the center of the bearing surface 171.

The electromagnet is initially calibrated by first loosening the screws 130 and 132 and then, with the armature held in attracted position, the magnet is moved to the

position where it causes the trip bar to just release the latch 121 after which the screws 130 and 132 are tightened to securely hold the core member in position.

The cam 165 is then rotated to bring the lowest point of its periphery into engagement with the adjusting screw 161 after which the screw 161 is adjusted so that the armature 131 almost touches the projecting member 155 (Figs. 2 and 3) on the trip bar 115 and the lock nut 163 is then tightened to lock the screw 161 in its adjusted position.

As shown in Fig. 3, the armature 131 is adjusted to trip the interrupter in response to overload currents of high value. In this adjusted position, the armature 131, biased by the spring 139 against the cam 165, occupies the position of greatest retraction permissible by adjustment of the cam 165. This position of the armature 131 provides the greatest main air gap between the armature and the pole face 147 and the smallest air gap between the armature 131 and the auxiliary pole face 151. This decreases the forward pull of the magnet for a given value of overload current and increases the value of current required to operate the trip magnet and trip the interrupter. Clockwise rotation of the cam 165 from the position in which it is shown in Fig. 3 moves the armature 131 clockwise about its pivot 133 thereby decreasing the main air gap and increasing the secondary air gap. This has the effect of increasing the forward pull of the magnet on the armature and of decreasing the back pull opposing tripping movement of the armature. When the device is adjusted to a position below the highest position to which it is capable of adjustment, the electromagnetic trip device will be actuated in response to overload currents of lesser magnitude to trip the breaker.

By way of example, assuming that the breaker is rated to carry a normal load indefinitely without actuating the trip device, the bimetal 103 may be calibrated to trip the breaker with an inverse time delay in response to overload currents of, for instance, between 100% and 300% of the normal rated current. The electromagnetic trip device may be calibrated and adjusted to instantaneously trip the breaker in response to overload currents of, for instance, between 300% and 1100% of rated current depending on the adjustment of the armature 131. Assuming that the trip device is calibrated to the above arbitrary values, then with the cam 165 adjusted so that the highest point of the cam 165 engages the adjusting screw 161, the armature 131 will be correspondingly moved closer to the pole face 147 and the electromagnet will operate to instantaneously trip the breaker in response to overload currents of 300% or more of rated current. If the cam 165 is rotated to bring the lowest point thereon into engagement with the adjusting screw, the armature 131 will be moved away from the pole face 147, and the armature will not be attracted until the occurrence of an overload current of 1100% of normal. By adjusting the cam 165 to any point between the maximum and minimum settings, the magnet will function to instantaneously trip the breaker in response to an overload current of a minimum value corresponding to the particular setting of the device. Thus, the trip device may be set to cause instantaneous tripping of the breaker in response to a minimum overload current of, for example, 300%, 500%, 700%, etc., up to approximately 1100% of normal rated current. If the device is adjusted to instantaneously trip the breaker at a minimum overload current of, for instance, 700% of normal, the bimetal element 105 will function to trip the breaker after a time delay in response to overload currents of any value between 100% and 700%, or between 100% and the particular minimum current value between 300% and 1100% to which the magnet is adjusted.

Figure 6 illustrates a modified embodiment of the tripping electromagnet in which the armature is provided with knife-edge pivots and the armature biasing spring is

7 connected thereto and arranged so that the bias of the spring remains even more substantially constant throughout the armature travel than with the arrangement previously described. The electromagnet indicated generally at 184 in Fig. 6 includes a U-shaped laminated core 185 which is mounted on the bracket 109 in the trip device in the same manner as the magnet 105 shown in Figs. 1 and 2, by means of screws 187 and 189. An armature 191 is provided with spaced knife-edge pivot members 193 seated in V-shaped bearing surfaces 195 formed in one leg 194 10 of the outer laminations 197 of the core member. The inner laminations of the core member 185 are cut off as shown at 199, and a pair of springs 201 having one end hooked over the screw 187 is disposed within the recess formed by the end of the laminations and the extension of the outer laminations 197. The other end of the springs 201 is attached to the armature 191 by means of inwardly bent ears 202 on the outer laminations at a point adjacent the pivoted end of the armature. The springs 201 apply a biasing force to the armature, biasing the armature to unattracted position with a very small moment arm.

15 The outer laminations 197 on the other leg 203 of the core member are bent at right angles and lie adjacent the ends of the other laminations of the fixed core members. Projections 205 of the outer laminations 197 extend toward the armature and are bent inwardly to form small auxiliary pole pieces 207 which, when the magnet is energized, exert a back pull on the armature 191. The auxiliary pole pieces 207 provide a limited path for at least a portion of the magnetic flux to thereby provide a differential pull on the armature 191 which is varied according to the adjustment of the armature relative to the leg 203 of the core members and the auxiliary pole piece 207.

20 The armature is adjusted in the previously described manner by means of the cam 165 and shaft 167. The cam 165 engages the inner end of an adjusting screw 209, mounted in an ear 211 of a member 213 secured to the armature 191 and locked in adjusted position by means of a lock nut 215. The member 213 is provided with an arcuate clearance slot 217 through which the shaft 167 extends, the shaft 167 having a bearing in one of the outer laminations 197.

25 The operation of the electromagnet 184 (Fig. 6) is similar to that of the electromagnet 105 (Fig. 3). The arrangement of the spring 201 relative to the pivot 193—195 is such that as the armature 191 is operated toward the attracted position, the line of action of the spring moves toward the pivot point of the armature shortening the moment arm by which the force of the spring 201 is applied to the armature. As the armature 191 moves toward attracted position, the point 202 at which the springs 201 are attached thereto causes a slight tensioning of the springs but this increased tension is offset by the shortening of the moment arm of the springs. This results in a substantially constant bias on the armature throughout its travel. This also applies to the several positions to which the armature can be adjusted by means of the cam 165. That is, the armature will be biased by substantially the same force in each of its adjusted positions.

30 From the foregoing description, it will be seen that the invention provides a circuit breaker having an improved trip device embodying an electromagnetic trip device embodying an electromagnetic trip means in which a variable differential pull is produced on the armature to permit a wide range of adjustment of the minimum overload current value required to trip the breaker. The invention provides means for quickly restoring the armature to unattracted position and also for maintaining substantially constant biasing force on the armature.

35 While the invention has been disclosed in accordance with the provisions of the patent statutes, it is to be understood that various changes in the structural details

5 and arrangement of parts thereof may be made without departing from some of the essential features of the invention. It is desired, therefore, that the language of the appended claims be given as reasonably broad interpretation as the prior art permits.

40 We claim as our invention:

1. A circuit interrupting device comprising an energizing winding, a U-shaped fixed core structure disposed to be energized by overload currents of predetermined value flowing in said winding, an armature pivotally supported on one leg of said U-shaped core structure, biasing means disposed adjacent the pivot of said armature normally biasing said armature to unattracted position, non-magnetic means mounted on said armature and having an angular portion extending from the armature and adjacent the other leg of said U-shaped core structure, a rotatable cam member engaging said non-magnetic member and rotatable to adjust the position of said armature relative to said U-shaped core structure, manual means operatively related to said cam member for rotating said cam member, and adjusting means supported in said non-magnetic member and adjustably engaging said cam member for varying the initial position of said armature.

2. A circuit interrupting device comprising an energizing winding, a U-shaped fixed core member disposed to be energized by overload current of predetermined value flowing through said winding, an armature pivotally supported on one leg of said U-shaped core member, biasing means disposed adjacent the pivot of said armature for biasing said armature to unattracted position with a relatively small moment arm, a member of non-magnetic material secured to said armature and having an angular portion extending from said armature and adjacent the other leg of said U-shaped core member, adjusting means mounted in said non-magnetic member and movable with said armature, a cam member engaging said adjusting means, means operatively related to said cam member for manually rotating said cam member to selectively position said armature relative to said core member to vary the minimum current required to operate said armature, and said adjusting means being adjustable to vary the initial position of said armature relative to said core member.

3. A circuit interrupting device comprising an energizing winding, a U-shaped core member disposed to be energized by said winding, an armature having one end pivotally supported on one leg of said U-shaped core member and the other end free, spring means disposed adjacent the pivot of said armature biasing said armature to a position whereby one side of said armature forms a main air gap with the other leg of said U-shaped core member for producing a forward pull on said armature, said other leg of said U-shaped core member having a member of magnetic material extending around the free end of the pivoted armature to the opposite side of said armature forming a secondary air gap with said armature for producing a back pull on said armature, a non-magnetic member secured to said armature and extending adjacent to said other leg of said U-shaped core member, a cam member engaging said non-magnetic member and movable to vary the position of said armature relative to said U-shaped core member and said magnetic member to vary said main air gap and said secondary air gap, and manual means for moving said cam member.

4. A circuit interrupting device comprising an energizing winding, a U-shaped core member disposed to be energized by said winding, a movable armature, means slidably and pivotally supporting one end of said armature on one leg of said U-shaped core member for pivotal movement and for sliding movement toward and away from said one leg, spring means normally biasing both ends of said armature away from said core structure so that said armature forms a main air gap with the other

leg of said core member and a second air gap with said one leg of said core member, said core member upon energization thereof by said winding attracting and slidably moving said one end of said armature to said core member and then pivotally moving said armature to close said main air gap, and said spring means upon deenergization of said winding slidably moving the pivoted end of said armature away from said core member to cause quick pivotal movement of said armature to unattracted position irrespective of any residual magnetism in said core structure.

5. A circuit interrupting device comprising an energizing winding, a U-shaped core member disposed to be energized by said winding, a movable armature, means slidably and pivotally supporting one end of said armature on one leg of said U-shaped core member for pivotal movement and for sliding movement toward and away from said one leg, spring means normally biasing both ends of said armature away from said core structure so that said armature forms a main air gap with the other leg of said core member and a second air gap with said one leg of said core member, said core member upon energization thereof by said winding attracting and slidably moving said one end of said armature to said core member and then pivotally moving said armature to close said main air gap, and said spring means upon deenergization of said winding slidably moving the pivoted end of said armature away from said core member to cause quick pivotal movement of said armature to unattracted position irrespective of any residual magnetism in said core structure, and adjusting means for engaging and positioning the armature relative to said core member to vary the main air gap and thereby vary the minimum current required to operate said armature.

6. A trip device for a circuit interrupter operable to effect opening of said interrupter comprising an electromagnet including an armature pivoted at one end and having the other end free, a fixed U-shaped core member disposed on one side of said armature to operate said armature upon energization of said electromagnet in response to overload currents of predetermined value, an auxiliary core member extending from one leg of said U-shaped core structure around the free end of the pivoted armature and disposed on the other side of the free end of said armature to restrain said armature against operation in response to overload currents below said predetermined value, pivot means pivotally supporting the other end of said armature on the other leg of said core structure, spring means disposed adjacent the pivoted end of said armature and connected to said armature in a manner to bias said armature to unattracted position with a relatively small moment arm, an extension of non-magnetic material on said armature, manual means comprising a rotatable cam for engaging said non-magnetic extension and adjusting said armature relative to said fixed core member and said auxiliary core member to vary the minimum overload current required to operate said armature.

7. A trip device for a circuit interrupter operable to effect opening of said interrupter comprising an electromagnet including an armature pivoted at one end and having the other end free, a fixed U-shaped core member disposed on one side of said armature to operate said armature upon energization of said electromagnet in response to overload currents of predetermined value, an auxiliary core member extending from one leg of said U-shaped core structure around the free end of the pivoted armature and disposed on the other side of the free end of said armature to restrain said armature against operation in response to overload currents below said predetermined value, pivot means pivotally supporting the other end of said armature on the other leg of said core structure, spring means disposed adjacent the pivoted end of said armature and connected to said armature in a manner to bias said armature to unattracted position

with a relatively small moment arm, an extension of non-magnetic material on said armature, manual means comprising a rotatable cam for engaging said non-magnetic extension and adjusting said armature relative to said fixed core member and said auxiliary core member to vary the minimum overload current required to operate said armature, and adjusting means on said extension engaging said rotatable cam for adjusting the initial position of said armature.

10. A trip device for a circuit interrupter operable to effect opening of said interrupter comprising an energizing winding, a fixed U-shaped core structure disposed to be energized by said winding, a movable armature, spaced knife-edge pivot means on said armature engaging spaced V-shaped bearings in one leg of said core structure to pivotally support said armature on said one leg of said U-shaped core structure, adjusting means comprising a manually operable cam engaging a part movable with said armature for adjusting the position of said armature relative to said fixed core structure, spring means connected under tension to said armature adjacent said pivot means and to a fixed member applying a force biasing said armature to unattracted position with a predetermined initial moment arm, said spring means moving between said spaced pivot means when said armature is operated, said spring means being connected to said armature so that upon adjustment of said armature the line of action of said spring means is moved relative to said pivot means thereby changing the moment arm so as to cause the spring means to apply substantially the same biasing force to said armature in all of the adjusted positions of said armature.

9. A circuit interrupting device comprising an energizing winding, a U-shaped fixed core member disposed to be energized by current of predetermined value flowing through said winding, a pivoted armature, spaced pivot means on said armature engaging spaced V-shaped bearings on one leg of said core member pivotally supporting said armature on said one leg of said U-shaped core member, biasing means connected under tension to said armature adjacent to said pivot means biasing said armature with a predetermined moment arm, the line of action of said biasing means being disposed to be moved between said spaced pivot means by operation of said armature to vary said moment arm and thereby cause said biasing means to bias said armature with a substantially constant force during the operation of said armature, adjusting means comprising a manually operable cam engaging a part movable with said armature for adjusting the position of said armature relative to said fixed core member to vary the minimum current required to operate said armature, and adjustment of said armature causing said biasing means to apply substantially the same biasing force to said armature in each of the adjusted positions of said armature.

10. A trip device for a circuit interrupter operable to effect opening of said interrupter comprising an energizing winding, a U-shaped fixed core member disposed to be energized by currents of predetermined value in said winding, a pivoted armature, spaced pivot means on said armature pivotally supporting said armature on one leg of said U-shaped core member, a member of non-magnetic material secured to said armature and having an angular portion extending adjacent the other leg of said U-shaped core member, a stepped cam member engaging said angular portion of said non-magnetic member and movable to adjust said armature to a plurality of positions relative to said fixed core member to thereby vary the minimum current required to operate said armature, spring means biasing said non-magnetic member into engagement with said cam member, said spring means being connected under tension to said armature and to a fixed member in a manner so that adjustment of said armature moves the line of action of said spring means relative to said pivot means to thereby cause

said spring means to bias said armature with substantially the same force in all positions of said armature.

11. A circuit interrupting device comprising a trip member operable to effect opening of said interrupter, an energizing winding, a U-shaped core member disposed to be energized by said winding, an armature pivotally supported on one leg of said core member and operable upon energization of said winding in response to overload currents of predetermined value to engage and actuate said trip member, said trip member extending between said core member and said armature, cam means operable to selectively position said armature relatively to said core member to vary the minimum overload current required to actuate said armature, and adjusting means for simultaneously adjusting the position of said core member and the position of said armature relative to said trip member while said armature remains in substantially the same position relative to the core member.

12. A circuit interrupting device comprising a trip member operable to effect opening of said interrupter, an energizing winding, a U-shaped core member disposed to be energized by said winding, an armature pivotally supported on one leg of said core member and operable upon energization of said winding in response to overload currents of predetermined value to engage and actuate said trip member, said trip member extending between said core member and said armature, cam means operable to selectively position said armature relatively to said core member to vary the minimum overload current required to actuate said armature, adjusting means for engaging said cam means and adjusting the initial position of said armature relative to said cam means, and adjusting means for simultaneously adjusting the position of said core member and the position of said armature relative to said trip member.

13. A circuit interrupting device comprising an energizing winding, a U-shaped core member disposed to be energized by said winding, an armature pivotally supported on one leg of said U-shaped core member, a member of non-magnetic material secured to said armature and extending adjacent the other leg of said U-shaped core member, a cam member engaging said non-magnetic member and operable to selectively position said armature relative to said core member, a shaft supporting said cam member for rotation therewith, means defining a concave seat in the other leg of said U-shaped core member for receiving and supporting one end of said shaft, spring means having an opening therein for receiving and rotatably supporting the other end of said shaft, biasing means for biasing said armature to unattracted position against said cam member and for returning said armature to said unattracted position upon opening of said interrupter, said one end of said shaft moving sideways in said convex seat to move said shaft axially against the bias of said spring means to resiliently absorb the blow of said armature when said armature is returned to unattracted position.

14. A circuit interrupting device comprising an energizing winding, a U-shaped core member disposed to be energized by said winding, an armature pivotally supported on one leg of said U-shaped core member, adjusting means comprising a member of non-magnetic material mounted on said armature, a cam member engaging said adjusting means, a shaft supporting said cam member for rotating said cam to selectively position said armature relative to said core member, means defining a conical seat in the other leg of said core member for receiving and pivotally supporting one end of said shaft, detent means on said shaft, spring means pivotally supporting the other end of said shaft and having means thereon engaging said detent means to resiliently hold said shaft and said cam member in the selected position, said spring means biasing said one end of said shaft into said conical seat, biasing means biasing said armature to unattracted position in which said adjusting means en-

gages said cam member, said shaft moving laterally on said conical seat and axially against the bias of said spring means to act as a resilient stop for said armature when said armature is moved to unattracted position, and said spring means then moving said one end of said shaft back to the center of said conical seat.

15. A circuit interrupting device comprising an energizing winding, a U-shaped core member energized by said winding, a movable armature, slideable pivot means at one end of said armature supporting said one end of said armature on one leg of said U-shaped core member for sliding movement toward and away from said one leg of said core member, said armature being pivotally movable about said pivot means, spring means acting on said armature at a point between said pivot means at said one end of said armature and the other end of said armature biasing both ends of said armature away from said core member against fixed stop means to normally provide a relatively small air gap at the pivoted end of said armature and a larger main air gap at the other end of said armature, said core member when energized first slidably moving said pivot means and said pivoted end of said armature toward said core member to reduce the magnetic reluctance while said main air gap remains open and then pivotally moving said armature about said pivot means to attracted position to close said main air gap, and said spring means upon deenergization of said core members first slidably moving said pivot means and said pivoted end of said armature away from said core member reestablishing said air gap at said pivoted end of said armature to increase the magnetic reluctance and then pivotally moving said armature about said pivot means to the unattracted position.

16. A circuit interrupting device comprising an energizing winding, a U-shaped core member disposed to be energized by said winding, a movable armature having a pivot in one end thereof, support members on one leg of said U-shaped core member having slots therein for receiving and slidably supporting said pivot to permit movement of said armature about said pivot and sliding movement of said pivoted end of said armature toward and away from said one leg of said core member, spaced fixed stop means at opposite ends of said armature, a spring applying a force to said armature at a point between said pivot and the other end of said armature normally biasing the ends of said armature to the unattracted position against said spaced fixed stop means to provide an air gap at each end of said armature, said core member when energized slidably moving said pivoted end of said armature toward said one leg of said core member to first close the air gap at said pivoted end of said armature while the air gap at the other end of said armature remains open and then pivotally moving said armature about said pivot to close the air gap at said other end of said armature, said spring upon deenergization of said core member first slidably moving said pivoted end of said armature away from said core member against one of said stop means and then pivotally moving said armature to unattracted position against another of said stop means.

17. A circuit interrupter comprising a U-shaped core member energized in response to abnormal conditions in the circuit of the interrupter, a movable armature, pivot means on one end of said armature, spaced support members on one leg of said U-shaped core, said support members having slots therein for receiving and supporting said pivot means for both pivotal movement and sliding movement toward and away from said one leg, spring means in said core member between said pivot means and the other end of said armature normally biasing said pivot means away from said one leg to provide a relatively small air gap and biasing said armature away from the other leg of said core to provide a relatively large main air gap, said core member when energized slidably mov-

ing said pivot means toward said one leg to reduce said small air gap while said relatively large air gap remains open and then pivotally moving said armature about said pivot means to close said main air gap, and said spring means upon deenergization of said core member first slidingly moving said pivot away from said one leg to reestablish said relatively small air gap and then pivotally moving the armature about said pivot means to unattracted position.

18. A circuit interrupting device comprising a trip member operable to effect opening of said interrupter, an energizing winding, a U-shaped core member disposed to be energized by said winding, an armature pivotally supported on one leg of said core member and operable upon energization of said winding in response to overload currents of predetermined value to engage and actuate said trip member, said trip member extending between said core member and said armature, a shaft pivotally supported at one end on said core member, spring means supporting the other end of said shaft and biasing said shaft toward said core member, cam means on said shaft operable to selectively position said armature relative to said core member to vary the minimum overload current required to actuate said armature, and adjusting means

5

for simultaneously adjusting the position of said core member and the position of said armature relative to said trip member while said armature remains in substantially the same position relative to the core member.
